UNITED STATES PATENT OFFICE.

COLONEL E. BRIGHT, OF COLUMBUS, OHIO.

DESIGN FOR HAT-TRIMMING.

No. 40,194.

Specification for Design.

Patented July 27, 1909.

Application filed May 1, 1909. Serial No. 493,440. Term of patent 7 years.

To all whom it may concern:

Be it known that I, COLONEL E. BRIGHT, a citizen of the United States, residing at Columbus, in the county of Franklin and State of Ohio, have invented a new, original, and ornamental Design for Hat-Trimming, of which the following is a specification, reference being had to the accompanying drawing, forming part thereof.

The figure is a face view showing the design of the trimming.

I claim:

The ornamental design for a hat trimming, as shown.

COLONEL E. BRIGHT.

Witnesses:

A. L. PHELPS,
L. CARL STOUGHTON.
